AUTOMATIC SIGNAL LIGHT

Application filed December 16, 1929. Serial No. 414,606.

The invention relates to automatic signal lights such as are used at road intersections and it is the object of the invention to clearly indicate the duration of each signal before a change will be effected. This is advantageous not only for the motorist who is approaching a signal light, but also for the pedestrians who are crossing the road. It is a further object of the invention to obtain this result with a simple construction as hereinafter set forth.

In the drawings:

Figure 1 is a perspective view of my improved signal light;

Figure 2 is a vertical longitudinal section partly in elevation;

Figure 3 is a horizontal section;

Figure 4 is a development in a single plane of the cylinder surface showing the relative arrangement of the translucent and opaque segments thereof.

As illustrated, A is an outer casing preferably of rectangular form and which is provided on its four sides with window openings B through which the signal light is displayed. These openings are arranged at the upper end of the casing A and each is provided with a vertical elongated narrow slot C extending downward therefrom to near the lower end of the casing.

Rotatively mounted within the casing A is a cylinder D which has translucent segments of the different signal colors such as green and red and also opaque segments.

These segments are arranged as shown diagrammatically in Figure 4 in which E, E', E² and E³ are each arcs of ninety degree angles and alternately of contrasting colors. For instance, the segments E E² may be

40 green in color and the segments E' E³ red. These segments are of a vertical height corresponding to the vertical height of the window opening B, but below these openings the colored translucent portion of each segment

45 is continued downward to correspond to the length of the slot C. These downwardly extending portions are not, however, the full width of the ninety degree arcs but are cut off by opaque segments F. The latter are of 50 wedge form being narrow at their upper ends

and having an oblique side F' extending down to the lower end which is substantially the full ninety degree arc.

With the arrangement as thus far described it is evident that if the signal light is placed within the cylinder D the translucent segments E, E', E², E³ will be displayed through the windows B on the several sides of the housing, green color being displayed on two opposite sides and red on the opposite sides which are at right angles thereto. At the same time each of these colors will be displayed through the adjacent slot C throughout its entire length. If now a rotary movement is imparted to the cylinder in a direction to cause the oblique edges F' of the opaque segments F to move past the slots C. This will cause a gradual shortening of the light column displayed through said slots, and this will indicate to the motorist or pedestrian the length of time before a change in signal.

The mechanism for rotating the cylinder D may be of any suitable construction which imparts a timed rotational movement thereto. As illustrated, I have employed a reciprocating electro-magnetic motor comprising the electro-magnet G, a ratchet lever H carrying the armature I for said magnet and a pawl J for engaging a ratchet wheel K. This ratchet wheel is mounted on a shaft L which also supports the drum D and the arrangement is such that the drum will be rotated step by step through successive electrical impulses passed through the magnet G. To effect a quick shifting from one column to another, I preferably employ a jump connection between the drum D and the shaft L which is operated at the instant when the slot C is entirely covered by the opaque segment F. This jump connection as shown is formed by a spring M constituting a resilient torque connection between the shaft and drum together with a brake N applied to the periphery of the head O at the upper end of said drum. The head O has cut away portions P at the end of each quarter segment, the arrangement being such that the brake will cause the drum D to lag behind the movement of the ratchet wheel K and shaft L until the cut away por-

tion P is reached, whereupon the release of the braking pressure will permit the spring M to suddenly jump the drum D forward.

The light Q arranged within the drum D may be of any suitable construction but as shown is attached to a socket on a conduit R passing downward through the hollow shaft L.

In operation, the rotation of the motor is timed by the pulsations of the current in the circuit including the electro-magnet G, or it may be timed in any suitable way such as by employing a synchronous motor instead of a reciprocating pulsating motor. Whenever 15 there is a change in the signal the line of light in the slot C is extended to the full length and will gradually shorten at a uniform rate until it completely disappears as the signal changes. Thus all observers will 20 know approximately the length of time before the change in signals.

What I claim as my invention is:

1. In an automatic light signal the combination with means for alternately and periodically displaying contrasting colors, of means for progressively decreasing the extent of one color throughout its period of duration at a uniform rate to a predetermined limit of area and suddenly for the remainder of the area. 25
2. In an automatic light signal, the combination with means for alternately and periodically displaying contrasting colors throughout an extended area, of means for progressively decreasing the extent of area during 30 the period of duration of each contrasting color at a uniform rate to a predetermined limit and suddenly for the remainder of the area. 35
3. In an automatic light signal, the combination with means for alternately and periodically displaying contrasting colors through a large window and a narrow slot extension thereof, of means for progressively decreasing the length of the line of light displayed through said slot throughout the period of duration of each color. 40
4. An automatic signal light comprising a source of light, a hollow screen surrounding the same having translucent portions of contrasting colors, and opaque portions, an outer casing having a large display window and an elongated slot extending therefrom and timing means for relatively moving said screen and outer casing to alternately and periodically display the contrasting colors through said window and to progressively diminish the illuminated length of said slot throughout the duration of the period of each color. 45
5. An automatic signal comprising a source of light, a revoluble cylinder screen surrounding said light and having translucent portions of contrasting colors, an opaque portion, an outer casing having a large window and an elongated narrow slot extending therefrom, the direction of extension of said

slot being oblique to one edge of said opaque portion and timing means for rotating said cylinder whereby said contrasting colors are alternately displayed through said window and throughout the length of said slot, the illuminated length of said slot being progressively diminished by said opaque portion throughout the duration of the period of each color. 70

6. An automatic signal comprising a source of light, a revoluble screen surrounding said light and being provided with translucent portions of contrasting colors, and opaque portions intermediate the contrasting color portions with one edge thereof oblique to the axis of the cylinder, an outer casing having a large display window and an elongated narrow slot extending therefrom parallel to the axis of said cylinder and timed means for rotating said cylinder to periodically change the color displayed through said window and throughout the length of said slot, the length of illuminated portion of said slot being progressively diminished by said opaque portion throughout the duration of each period. 80

7. An automatic signal comprising a housing having a plurality of sides, each provided with a display window and an elongated slot extending therefrom, a source of light within said housing, a revoluble screen surrounding said light and having translucent portions alternately of contrasting colors and intermediate opaque portions having one edge oblique to the axis of the cylinder and timed means for rotating said cylinder whereby the contrasting colors are alternately displayed through said window and throughout the length of said slot with a progressive diminution in the illuminated length of said slot throughout the duration of each period. 90

8. An automatic signal comprising a housing having a plurality of sides, each provided with a display window and an elongated narrow slot extending therefrom, a source of light within said housing, a revoluble screen surrounding said light and having adjacent translucent portions alternately of contrasting colors and registering with said window and slot and intermediate opaque portions having one edge oblique to the axis of the cylinder for registering with said slot only, timed means for rotating said cylinder whereby said contrasting colors are alternately displayed through said window and throughout the length of said slot with a progressive diminution in the elongated length of said slot by the oblique edge of said opaque portion and means accelerating said cylinder at the complete closing of said slot by said opaque portion to quickly reverse the color displayed through said window. 100

In testimony whereof I affix my signature.

HARVEY G. MOSHER.
